UNITED STATES PATENT OFFICE.

OREN CLAY BUELL, OF COLUMBUS, OHIO, ASSIGNOR TO THE FEDERAL GLASS COMPANY, OF COLUMBUS, OHIO, A CORPORATION OF OHIO.

DESIGN FOR A TUMBLER OR ARTICLE OF SIMILAR NATURE.

Application filed December 23, 1926. Serial No. 20,125. Term of patent 14 years.

To all whom it may concern:

Be it known that I, OREN CLAY BUELL, a citizen of the United States, residing at Columbus, in the county of Franklin and State of Ohio, have invented a new, original and ornamental Design for a Tumbler or Article of Similar Nature, of which the following is the specification, reference being had to the accompanying drawing, forming a part hereof.

2—2 of Figure 1 presenting a magnified showing of the convexity of the broad stripes which define and enclose the diamond areas.

I claim:

The ornamental design for a tumbler or article of similar nature, as shown, and described.

OREN CLAY BUELL.
